UNITED STATES PATENT OFFICE.

LEONARD JOSEPH DENNIS, OF REGINA, SASKATCHEWAN, CANADA.

CLARINET TUNING-SLIDE.

1,163,222.

Specification of Letters Patent.

Patented Dec. 7, 1915.

Application filed June 5, 1915. Serial No. 32,329.

To all whom it may concern:

Be it known that I, LEONARD J. DENNIS, a citizen of the Dominion of Canada and a subject of the King of Great Britain and 5 Ireland, residing at Regina, in the Province of Saskatchewan and Dominion of Canada, have invented certain new and useful Improvements in Clarinet Tuning-Slides; and I hereby declare that the following is a full, 10 clear, and exact description thereof, reference being had to the accompanying drawings, which form part of this specification.

This invention is a novel improvement in means for tuning clarinets and like wind 15 musical instruments by correcting deviations in pitch from an absolutely correct tone. Its principal object is to provide novel means for manipulating the tuning slide of a clarinet or like instrument, which 20 means can be readily attached thereto, and by operating such means the slide can be adjusted until the desired pitch is obtained; and as applied to clarinets the pitch of the instrument can be regulated with one hand 25 while the instrument is being played by the other.

Another object is to provide a very simple adjusting means whereby only linear adjusting movements of the slide will be 30 caused, doing away with any twisting or turning motion of the parts of the slide; and whereby the most delicate adjustments can be made and absolute accuracy of pitch 35 procured between the extreme practical limits.

In the accompanying drawings I have illustrated the at present preferred practical embodiment of the invention and one or two modifications thereof, and will explain 40 the invention with reference to said drawings and summarize in the claims the essential features thereof for which protection is desired.

In said drawings:—Figure 1 is a side 45 view of the tuning slide of a clarinet or like wind instrument provided with my novel adjusting devices. Fig. 2 is a side view of Fig. 1 showing the adjusting device in section. Fig. 3 is a section on the line 3—3 50 Fig. 1. Fig. 4 is a detail section on line 4—4 Fig. 3. Fig. 5 is a detail view showing a slight modification of the adjusting devices partly in section. Fig. 6 is a view of

another modification of the adjusting devices.

In the drawings 1 and 2 designate the upper and lower members of the tuning slide of a clarinet, or like wind instrument, the member 1 having the usual tubular extension 1^a telescoping in the member 2 so that 55 said tuning slide can be lengthened or shortened by simply moving the members 1 or 2 from or toward each other. These said parts may be of any suitable construction, and are shown like those commonly in use in 60 clarinets and like instruments. In order to vary the pitch of the instrument the slide must be lengthened or shortened, to a 65 greater or less extent, depending upon the variations of pitch required.

Various devices have been heretofore designed for adjusting such tuning slides but most of them necessitate the stopping of 70 playing while the instrument is being adjusted, or the use of both hands to effect 75 the adjusting; or a twisting motion of one member relative to the other. By my invention all these objections are overcome and in the at present preferred form there- 80 of, illustrated in Figs. 1 to 4, I effect the adjustment of the tuning slide by the following means:—To the outer side of mem- 85 ber 1 is attached a depending bar 3, the upper end of which may be connected to a perforated plate 3^a attached to member 1 by screws as indicated in the drawings or in other suitable way. The lower part of bar 3 telescopes within a socket or guide 4 at- 90 tached to the lower member 2, and this guide 4 may be provided with a perforated front plate 4^a by which it is fastened to the member 2 by screws, as indicated in the drawings, or other suitable means. To the lower end of the plate 4^a is attached a pro- 95 jecting stud 4^b upon which is mounted a ro- tatable cam member 5, which cam member is provided on its inner face with a helical cam slot 5^c adapted to be engaged by a pin 3^e attached to the lower end of the bar 3, said pin projecting through a slot 4^e in the 100 plate 4^a. The cam slot 5^c is so graduated that in any position of the cam 5 the cam will be practically self-locking, that is the pressure or pull of the pin 3^e in the slot 5^c will not rotate the cam. By simply turning 105 the cam 5 on stud 4^b the members 1 and 2

will be moved toward or away from each other and the pitch accordingly changed. To prevent any casual movement of the cam 5 a locking nut 5^a may be screwed on the outer end of stud 4^b; and if desired a cap nut 5^b may also be screwed thereon to make a neat finish.

In Fig. 5 a rack 6 is shown as attached to member 1 in place of the bar 3, and may 10 be engaged with the guide 4. A pinion as 6^a is mounted on a stub shaft 6^b supported in bearings 6^c on plate 4^a and provided with a hand wheel 6^d. By rotating shaft 6^b the slide can be adjusted. The shaft 6^b can be 15 locked by any suitable means, as by a jam nut 6^e on its end as indicated in Fig. 5.

In Fig. 6 a threaded rod 7 may be attached to member 1 and engaged with a rotatable nut 7^a mounted in a support 7^c attached to the member 2; and by rotating nut 7^a the slide can be adjusted to vary the pitch.

With my invention the clarinet can be tuned with one hand while being played 25 with the other; the slide members have no relative rotation; the adjusting bar also serves as a key to prevent relative rotation of the slide-members. With such adjusting means there is no need for loosening, dis- 30 connecting, or displacing, any part of the instrument or adjusting any part except the tuning slide. Further the fingering arrangement or keying is not altered by adjusting the pitch. For some instruments 35 such adjusting means might be used for changing the key, but in an instrument like a clarinet it is not practical to change the key because such attempt to change the key of a clarinet would put the instrument out 40 of tune with itself; while my invention as applied to clarinets will enable the instrument to be quickly adjusted to absolutely correct pitch, without otherwise affecting the instrument which will remain perfectly 45 tuned in itself although the pitch may be slightly changed up to a quarter of a tone.

What I claim is:

1. In combination with a tuning slide for clarinets and like wind instruments; a bar 50 attached to one member of the slide and slidably engaging the other member thereof and adapted to prevent relative rotary

movement of said members, and means for moving said bar longitudinally to lengthen or shorten the slide.

55

2. In combination with the members of a tuning slide for clarinets and like wind instruments; a bar attached to one member and slidably engaging the other member to prevent relative rotary movement of said members, means engaging said bar to operate the same and thereby adjust the said members to or from each other and for holding the members in adjusted position.

3. In combination with the members of a tuning slide of a clarinet or like wood instrument; a bar attached to one member, a guide attached to the other member and engaged by said bar to prevent relative rotary movement of said members, and means adjacent the guide engaging said bar to move same longitudinally and hold the members in adjusted position.

4. In combination with the members of a tuning slide of a clarinet or like wood instrument; a bar fixedly attached to one member, and a rotatable cam attached to the other member and engaging said bar to adjust the same longitudinally.

5. In combination with the members of a tuning slide of a clarinet or like wood instrument; a bar fixedly attached to one member, a guide attached to the other member and engaged by said bar, and a rotatable cam engaging said bar to adjust same longitudinally and hold same in adjusted position.

6. In combination with the members of a tuning slide of a clarinet or like wood instrument; a bar fixedly attached to one member, a guide attached to the other member and engaged by said bar, a rotatable cam attached to said guide and having a helical cam slot, and a pin on the bar engaging said cam slot, substantially as de- 95 scribed.

In testimony that I claim the foregoing as my own, I affix my signature in presence of two witnesses.

LEONARD JOSEPH DENNIS.
